HINGE STRUCTURE

John D. Bolesky, Mansfield, Ohio, assignor to Westinghouse Electric & Manufacturing Company, East Pittsburgh, Pa., a corporation of Pennsylvania

Application October 27, 1934, Serial No. 750,303

8 Claims. (Cl. 53—5)

My invention relates to domestic electric cooking appliances, and particularly to sandwich toasters and waffle irons.

An object of my invention is to provide a relatively simple, inexpensive and easily manufactured and installed hinge structure for a pair of superposed casings.

Another object of my invention is to provide a hinge structure for a sandwich toaster that shall permit of selectively moving the upper casing relatively to the lower casing in a plurality of different paths, and also to hold the upper casing in a plurality of different operative positions relatively to the lower casing.

Other objects of my invention will either be pointed out specifically hereinafter, or will be apparent from a description of a preferred form of device embodying my invention.

In practicing my invention, I provide a lower hinge member of substantially L-shape having a slot therein, a substantially flat hinge link vertically movable in the slot in the lower hinge bracket and having an opening at its upper end substantially rectangular in shape, together with an upper hinge bracket also of substantially L-shape and having a lug portion to fit into the opening in the upper end of the hinge link.

In the drawings:

Figure 1 is a view, in rear elevation, of a sandwich toaster having associated therewith hinge structures embodying my invention;

Fig. 2 is a view in side elevation of the assembly shown in Fig. 1;

Fig. 3 is a view in rear elevation of one of the upper hinges;

Fig. 4 is a side view thereof;

Fig. 5 is a view in rear end elevation of a lower hinge bracket;

Fig. 6 is a bottom plan view thereof;

Fig. 7 is a view in side elevation of a hinge link;

Fig. 8 is an edge view thereof;

Fig. 9 is a view of a sandwich toaster showing the upper casing at an angle of substantially 90° relatively to the lower casing; and

Fig. 10 is a view similar to Fig. 9 but showing the upper casing in inverted position on a support.

In the toasting of sandwiches, it may happen that the operator is called upon to toast sandwiches of widely varying thicknesses, and it is, therefore, important that the hinge structures utilized with a sandwich toaster of this general kind shall permit of moving an upper casing in parallel-face relation relatively to the lower cas-

ing through relatively large distances. It is also desirable to be able to hold the upper casing in a partially opened position relatively to the lower casing and it may be necessary to have the two heating surfaces in coplanar position relatively to each other.

Referring to Figs. 1 and 2 of the drawings, I have there illustrated a plural casing sandwich toaster 11 comprising an upper casing 13, a lower casing 15, a base 17 and a support for the lower casing 15, which may be constituted by a plurality of tubular members 19, all in a manner now well known in the art.

I have not shown any heating means for the upper and the lower casings and more particularly, for the upper heating surface 21, and the lower heating surface 23, for the sake of clearness, but it is to be understood that any suitable or desired heating means may be located within the respective casings 13 and 15 in operative or heat transferring relation to the heating surfaces 21 and 23 also in a manner well known in the art. The upper casing 13 may have a heat insulated handle 25 mounted thereon at the front portion thereof, and a knob 27 on its upper surface, which knob 27 is adapted to support the upper casing 13 when in its fully opened position, as will be hereinafter more specifically pointed out.

I provide, preferably, two hinge structures including an upper hinge bracket 29, a lower hinge bracket 31, and a substantially flat hinge link 33 extending therebetween, and it will be evident that these hinge structures may be made "left" and "right" respectively, and it is to be understood that a description of one such hinge structure is illustrative of both with the exception that the other one is constructed oppositely to the one described.

The upper hinge bracket 29 includes a plate 35 adapted to be secured against the flat rear surface of casing 13 adjacent one side thereof, and having integral therewith a portion 37 extending at right angles thereto, which portion 37 has a lug 39 integral therewith, and extending at right angles thereto and in the same direction as plate 35. As will be noted from Fig. 1 of the drawings, the part 35 of the left-hand hinge bracket 29 (as viewed from the rear end of the toaster) extends toward the mid-portion of the casing, so that rivet heads 41 are hidden to some extent, these rivet heads being those used to secure the bracket 29 to the casing 13.

The lower hinge bracket 31 includes a flat plate 43 having rivet openings therein to receive rivets for securing it against the lower casing 15. The

portion 43 has integral therewith a portion 45 extending at right angles thereto, which portion 45 has two lugs 47 and 49 at the top and bottom thereof, respectively, extending at right angles to the plane of portion 45 or towards the portion 43. The lugs 47 and 49 are provided with openings 51 and 53 therethrough for a purpose to be hereinafter set forth.

A hinge link 33 includes an upper end portion 57 having a substantially rectangular opening 59 therein with an auxiliary recess 61 in the lower outer corner thereof, and a lower narrower bar portion 63 which is provided with a laterally extending short lug 65. The portion 63 of hinge link 33 fits into and extends through the openings 51 and 53 of the lower hinge bracket so that the hinge link may have vertical movement relative to the lower hinge bracket 31 when the two casings are in the positions shown in Figs. 1 and 2 of the drawings. The laterally extending lug 65 limits the upward movement of the hinge link 33 relatively to the lower hinge bracket 31 and it will be noted that the only movement of hinge link 33 relatively to lower bracket 31 is in a straight line vertically upwardly or downwardly direction.

The upper end portion 57 of the hinge link is located closely adjacent to and at one side of the portion 37 of upper hinge bracket 29, the lug 39 on portion 37 fitting into opening 59. When casing 13 is superposed on casing 15, lug 39 will extend substantially horizontally in opening 59, and rest on the bottom wall thereof or may be located closely adjacent to but slightly above the bottom wall of opening 59.

If it be assumed that an operator wishes to toast a sandwich of say one-half inch thickness, he may locate the same within or between the heating or baking surfaces 21 and 23 by raising the upper casing and its associated elements by the pivotally mounted handle 25, place the sandwich on the lower baking surface 23 and then permit the upper casing and the upper baking surface to rest upon the upper face of the sandwich. It will be noted that the upper casing can move upwardly through a distance determined by the height of opening 59, less the thickness of lug 39, without in any way causing upward movement of hinge link 33 in the lower hinge bracket. If it should happen that a sandwich to be toasted is thicker, so that the lug 39 will engage the upper wall of opening 59, then hinge link 33 will also be moved upwardly the necessary distance, this upward movement being, however, limited by lug 65 striking against flange 49.

Let it be assumed that the operator wishes to hold the upper casing 13 in partially opened position, such as is shown in Fig. 9 of the drawings, it is only necessary to turn the upper casing 13 by means of the handle 25, and the rear edge portion of lug 39 will move into auxiliary recess 61 while its originally upper surface will rest against the rear or outer wall of opening 59, substantially as shown in Fig. 9 of the drawings. It will be noted that this outer wall has a slight upward and outward slope which is just sufficient to insure that the upper casing and its associated parts will remain in the position substantially as shown in Fig. 9 of the drawings, once they have been moved thereinto and held there by the lug or lugs 39 in the auxiliary recesses 61, as has just been described.

Let it be further assumed that the operator wishes to have two independent coplanar heating surfaces, so that he desires to turn the upper casing through substantially 180° from its original

position. If it be assumed that he desires to move the upper casing from the position shown in Fig. 9 of the drawings to that shown in Fig. 10 of the drawings, he need only raise slightly the upper casing assembly, so that the lower edge of lugs 39 will be moved out of the auxiliary recess 61, when it will be possible to turn the casing 13 to the position shown in Fig. 10 of the drawings, where the upper end of knob 27 rests upon the surface 67 supporting the sandwich toaster.

Each hinge link 33 has a bend 69 therein just below the portion 57 the upper end portion of each hinge link being located a small distance closer to the side of the toaster. This is necessary so that the portion 37 of the respective upper hinge plates may move past the portion 45 of the respective lower hinge plates when the upper casing is turned to the position shown in Fig. 10 of the drawings.

The device embodying my invention thus provides a very simple hinge structure utilizing metal brackets bent to final shape, and a substantially flat hinge link so that my improved device embodies relatively simple, inexpensive and easily manufactured and installed hinge members. It will be noted that the element connecting the two hinge brackets has vertical movement only relatively to the lower hinge bracket and that the upper hinge bracket has a parallel face or vertical movement in the hinge link, as well as having a turning movement relatively thereto, and that the hinge link cooperates with the upper hinge bracket to hold the upper casing in a partially opened position relatively to the lower casing assembly.

Various modifications may be made in the device embodying my invention without departing from the spirit and scope thereof, and I desire, therefore, that only such limitations shall be placed thereon as are imposed by the prior art or are set forth in the appended claims.

I claim as my invention:

1. A cooking appliance comprising, in combination, a lower casing and an upper casing, hinge brackets on the respective casings, and a substantially flat link connecting the two brackets and having an opening therein adjacent the upper end materially larger than a portion of the upper hinge bracket received therein to permit a loose turning movement thereof in the opening.

2. A cooking appliance comprising a lower casing, an upper casing, a hinge bracket on each casing and a flat link connecting the two brackets, said flat link having limited straight line movement relatively to the lower bracket and having an opening therein adjacent to the upper end thereof, the upper hinge bracket having a portion materially smaller than the opening extending thereinto and loosely turning therein.

3. A cooking appliance comprising, in combination, a lower casing, an upper casing, and a hinge structure connecting the two casings and including a channel shaped hinge bracket secured to the lower casing and having substantially aligned openings in the spaced arms of the bracket, a hinge link vertically movable through said openings in the lower hinge bracket and a hinge bracket secured to the upper casing and having turning movement in the hinge link.

4. A cooking appliance comprising, in combination, a lower casing, an upper casing, and a hinge structure connecting the two casings and including a hinge bracket on the lower casing, a hinge link vertically movable in the lower hinge bracket and having an opening in its upper end

of substantially square shape with an extension at the lower outer corner and an upper hinge bracket on the upper casing having a flat lug located in the opening in the hinge link and adapted to have an edge portion fit into the extension with the lug resting against the rear wall of the opening to hold the upper casing at an angle of substantially 90° away from the lower casing.

5. A cooking appliance comprising, in combination, a lower casing, an upper casing, and a hinge structure connecting the two casings and including a lower hinge bracket on the lower casing, a hinge link vertically movable in the lower bracket and having an opening of substantially square shape at its upper end with an auxiliary recess at the lower outer corner and an upper hinge bracket on the upper casing and having a flat lug located in the opening in the hinge link in a substantially 10 horizontal position when the upper casing is closed on the lower casing, the flat lug fitting into the auxiliary recess and engaging the rear wall of the opening to hold the upper casing in substantially vertical position and the flat lug resting 15 in inverted position on the bottom wall of the opening when the upper casing is located coplanar with the lower casing.

6. A cooking appliance comprising, in combination, a lower casing, an upper casing, and a hinge structure connecting the two casings and including a lower hinge bracket on the lower casing, a hinge link vertically movable in the lower bracket

and having an opening of substantially square shape at its upper end and an upper hinge bracket on the upper casing having a flat lug located in the opening in the hinge link and selectively movable in the opening to raise the upper casing parallel to the lower casing and to turn the upper casing relatively to the lower casing.

7. A cooking appliance comprising, in combination, a lower casing, an upper casing, and a hinge structure connecting the two casings and including a hinge bracket on the lower casing, a hinge link secured to the lower hinge bracket, and having an opening in its upper end and an upper hinge bracket on the upper casing having a projection materially smaller than said opening extending thereinto and adapted to interlock with a portion of the hinge link surrounding said opening to hold the upper casing at a predetermined angle away from the lower casing.

8. A cooking appliance comprising, in combination, a lower casing, an upper casing, and a hinge structure connecting the two casings and including a lower hinge bracket on the lower casing, a hinge link secured to said lower hinge bracket and having an opening in its upper end and an upper hinge bracket on the upper casing having a projection materially smaller than said opening extending thereinto and selectively movable in the opening to raise the upper casing parallel to the lower casing and to turn the upper casing relatively to the lower casing.

JOHN D. BOLESKY.
